(57) **CLAIM**

The ornamental design for a vehicle, as shown and described.

DESCRIPTION

FIG. 1 is a front, right side perspective view of the vehicle of the present invention with the top on;

FIG. 2 is a rear, right side perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof;

FIG. 8 is a bottom view thereof;

FIG. 9 is a front, right side perspective view of the vehicle of the present invention with the top off;

FIG. 10 is a rear, right side perspective view thereof;

FIG. 11 is a right side view thereof;

FIG. 12 is a left side view thereof;

FIG. 13 is a front view thereof;

FIG. 14 is a rear view thereof;

FIG. 15 is a top view thereof; and,

FIG. 16 is a bottom view thereof.

The interior of the vehicle does not form part of the claimed design.
